UNITED STATES PATENT OFFICE.

SAMUEL N. McCLEAN, OF CLEVELAND, OHIO.

DISCHARGE-ACTUATED BREECH-LOADING GUN.

SPECIFICATION forming part of Letters Patent No. 715,839, dated December 16, 1902.

Application filed November 26, 1900. Serial No. 37,818. (No model.)

To all whom it may concern:

Be it known that I, SAMUEL N. McCLEAN, a resident of Cleveland, Ohio, have invented a new and useful Improvement in Discharge-
5 Actuated Breech-Loading Guns, which invention is fully set forth in the following specification.

My invention relates to breech-loading and discharge-actuated guns, and has for its object to utilize the force of the discharge for
10 operating the gun and controlling the recoil.

Upon the discharge of a piece of ordnance a large amount of energy is expended in a rearward direction, the effect of which is seen
15 in the movement of the large mass of the gun to the rear. Besides this rearwardly-directed energy there is also a large amount of energy expended in a forward direction, as evidenced by the tremendous power of the forwardly-
20 moving gases of discharge. Furthermore, the breech mechanism of large guns is frequently of such weight as to render a motor for operating the same quite desirable. The present invention, broadly stated, consists in opposing
25 the forwardly-directed energy of the gases of discharge to the rearwardly-directed energy of the recoil to the end that the recoil may be neutralized and the rearward recoil movement of the gun largely, if not entirely,
30 eliminated. Moreover, the invention consists in means for compelling the energy of recoil and of the gases of discharge to act in opposite directions upon and compress an elastic gas, as air, whereby a portion of the
35 energy of the discharge is stored in said compressed gas, and then utilizing the energy of this gas so compressed directly or indirectly as the power for operating the breech mechanism.

40 In carrying out my invention I oppose a part attached to the gun—as, for example, a piston—to a part, which may also be a piston, actuated by the gases of discharge and provide means for confining a gas, such as air, between said parts, whereby the air is compressed, shock to the gun and its carriage is avoided, and the energy stored in the compressed air is rendered available for operating the breech mechanism. Preferably I do
45 not directly employ the air compressed between the two pistons as the motive fluid for operating the motor attached to the breech

mechanism, but utilize this air as a power for compressing another supply of air in a suitable reservoir. This has the advantage that 55 the air between the pistons may have an initial tension imparted to it, and thus act to retain the parts in their proper relative positions when the gun is at rest. The initial tension of the air within the brake-cylinder need 60 not be very great, as sufficient movement of the opposing pistons is provided to develop the high pressure required to neutralize the recoil. By this means I avoid the necessity of maintaining a constant high pressure with- 65 in the brake-cylinder with the consequent leakage, as the high pressure is exerted only when the parts are under greatest stress and is then almost instantly reduced.

In the particular embodiment of my invention shown herein I have attached a pneumatic-brake cylinder to the gun-carriage and provided a piston attached to the gun and moving rearwardly in the cylinder when the gun is fired. A second piston is placed in 75 said cylinder to the rear of the first and is attached by a suitable rod to a sleeve surrounding the muzzle of the gun and provided with a suitable gas-nozzle for catching and controlling the gases of discharge and prolonging their action. This sleeve and attached gas-nozzle are given a sufficient travel or forward movement to enable them and their attached parts to acquire proper velocity to effectually oppose and overcome the recoil of 85 the gun. The gases are automatically controlled by the gas-nozzle to work at the required pressure and for the proper length of time, and for this purpose the gas-nozzle may be provided with automatically-operated 90 valves for closing and opening the port through which the projectile passes. Preferably these valves are closed by the gases of discharge upon the initial forward movement of the nozzle and opened by the terminal 95 rearward movement of the nozzle, the pressure of the gases within the nozzle being controlled by automatically-governed vents.

The breech-block employed is preferably of the interrupted-screw type having turning, sliding, and swinging movements in opening and closing the breech, and has these movements imparted to it by a single motor, whose motive power is derived from the air

compressed by the combined action of the recoil and the gases of discharge. As shown, this is a pneumatic motor housed between the hinge-arms of the carrier-tray and having its 5 axis of rotation around the hinge-pin of the tray. The rotary movement of the motor around this pin serves to impart to the breech-block its turning, sliding, and swinging movements, whereby the breech is opened and 10 closed. The motor is controlled by a suitable valve, which may be operated by a moving part of the gun upon recoil or counter-recoil or by hand, as desired.

Various mechanical expressions may be 15 given to the inventive idea involved in the gun which I have devised, and for purposes of illustration I have shown in the accompanying drawings one form which the same may assume.

20 Figure 1 is a side elevation of a field-gun embodying my invention, parts being shown in section. Figs. 1^a, 1^b, and 1^c are details of the automatic device for operating the valve controlling the motor for the breech-block. 25 Figs. 2, 3, and 4 are details of the brake-cylinder, brake-pistons, and gas-nozzle. Fig. 5 is a longitudinal sectional view of the gas-nozzle. Fig. 6 is a broken plan view of the breech of the gun, showing the breech-block and its operating-motor. Fig. 7 is a side elevation thereof with the breech open. Fig. 8 is a front elevation of the carrier-tray. Fig. 9 is a vertical section of the motor on line 9 9, Fig. 6. Fig. 10 is a horizontal section on the line 10 35 10, Fig. 9, the controlling-valve and its connecting-pipes being shown in diagram. Fig. 11 is a top plan view of the motor. Fig. 12 is a side elevation thereof. Fig. 13 is a longitudinal vertical section through the gun, the 40 gas-nozzle, and the brake-cylinder. Fig. 14 is a side elevation, and Fig. 15 a cross-section, of another form of the invention.

Referring to the drawings, 1 is the gun, mounted to slide in the cradle 2, supported 45 upon trunnions 3, turning in suitable bearings on the carriage. The gun has side ribs or flanges 4, rigidly secured one on either side thereof, which ribs enter grooved ways 5 in the cradle 2, whereby the gun is free to move in the 50 cradle in a longitudinal direction only. The brake-cylinder 6 is supported at its forward end by the cradle 2 and at its rear end by means of a band 7, passing over the breech end of the gun loosely enough to permit the gun to move 55 freely therethrough. Within the brake-cylinder is a piston 8, attached to a hollow piston-rod 9, extending out through the forward end of the cylinder and fixedly secured to the gun by means of a band 10, carrying a downwardly-projecting arm 11, the band 10 being shrunk or otherwise secured on the gun, so 60 that it and its connected piston 8 partake of the longitudinal movements of the gun upon recoil and counter-recoil. A sleeve 12 is mounted to reciprocate upon the muzzle end of the gun and has a rearwardly-projecting rod 13 secured to the under side thereof.

which rod is made in two sections, as shown, so that its length may be adjusted, and bears on its rear end a piston 14. As the sleeve 12 70 reciprocates on the muzzle end of the gun the forward section of the rod 13 is guided in an opening 15, provided in the downwardly-projecting arm 11 of the sleeve 10, while the rearward section of the rod 13 passes through the 75 hollow piston-rod 9 and the piston 8, so that the piston 14 on said rod 13 occupies a position in the cylinder 6 to the rear of the piston 8, all of which will be readily understood by inspecting Figs. 3, 4, and 13. Referring more 80 particularly to Fig. 5, it will be observed that the reciprocating sleeve 12 bears on its forward end a gas-nozzle 16, provided with an opening 17 in line with the bore of the barrel. This nozzle is formed by a cylinder having 85 an internal diameter exceeding that of the sleeve 12 and fixedly secured to the forward end of said sleeve. Two swinging valves 19 are pivoted to the plug 20 in such manner that when they swing toward each other they 90 close or partially close the port 17 in the plug 20, through which the projectile and the gases of explosion must pass to escape from the gun. These valves 19 are flap-valves provided with tail portions projecting beyond their pivots, 95 the body of the plug 20 being cut away sufficiently to permit the swing of the tails of said valves in their closing and opening movements. Mounted to slide in grooves 23 in line with the swinging movements of the tails 100 of the valves 19 are two pins 21, having inwardly-projecting lugs 22, which engage the forward face of the muzzle of the gun when the sleeve 12 and the nozzle 16 are in their rearmost position, the grooves 23 in which the 105 pins 21 play being slightly longer than the said pins in order that the pins may slide rearwardly to permit the closing movements of the valves 19 when the sleeve 12 and the nozzle 16 are in their forward position and 110 may be advanced so as to impinge upon the tails of the valves and open them when the nozzle is in the rearmost position, with the lugs 22 engaging the forward face of the muzzle of the gun. Any suitable vents for permitting the escape of the gas from the nozzle 115 may be provided—as, for example, the vents 24, formed in the valves 19. The size of these vents will determine the length of time during which the gas will act upon the nozzle and 120 hold it and its connected parts in a forward position, and therefore afford means whereby the action of the gas may be regulated and controlled.

Referring now more particularly to Figs. 6 125 to 12, inclusive, 25 is a breech-block of the mutilated screw-thread construction provided with worm-teeth 26 on the periphery of its rear end and a longitudinally-extending rack 27. A carrier-tray 28 is hinged to one side 130 of the breech of the gun by means of a pin 29 extending through lugs 30, projecting from the breech end of the gun, and arms 31, attached to the tray. This breech-block and

tray may be of the ordinary construction and need not therefore be further described. The motor for operating the breech-block is best shown in Figs. 9 to 12, inclusive, and consists of a sleeve 32, keyed to the pin 29 by means of a key 33 and having a vertically-disposed radially-projecting wing 34. This sleeve, with its radially-projecting wing, is inclosed in a cylinder formed of the two halves 35 and 36, the cylinder being of such a diameter as to permit the wing to move therein and yet maintain practically fluid-tight contact with the internal surface of the cylinder. One of the halves of the cylinder, as 15 35, is provided with an annular rib or flange 37, having radially-extending worm-teeth 38 formed thereon, as well as similar rack-teeth 39. The motor-cylinder is preferably inclosed in a casing 40, formed of upper and 20 lower halves for the purpose of convenience of assemblage, and suitable packing 41 is introduced between the sleeve 32, the motor-cylinder 35, and the casing 40 in order to prevent any leakage of the motor fluid. The 25 pintle 29 has formed therein longitudinal ducts 42 and 43, which extend upward through the pintle and open outward through the sleeve 32 into the cylinder 35, one on either side of the wing 34, and the cylinder 35 has 30 a radially-formed inwardly-projecting wing 44, (best shown in Fig. 10,) which forms a fluid-tight joint with the outer surface of the sleeve 32. Flexible pipes 45 and 46 connect the lower ends of ducts 42 and 43 with 35 the valve-casing 47, having therein any suitable valve for admitting pressure to one of the pipes 45 and 46 and permitting it to escape from the other, as may be desired. The valve herein shown consists of a cylindrical piston 48, playing in the cylinder 47 and having an annular groove 49 formed between its ends. The cylinder 47 has two ports 50 and 51 formed in its opposite ends, communicating directly with the atmosphere, and midway 45 between its ends the port 52, leading to the source of fluid-pressure. When the valve is in the position shown in Fig. 10, pressure is allowed to escape from the motor-cylinder on one side of the wing 34 via duct 43, pipe 45, 50 and port 50 in the valve-casing 47, while pressure is admitted to the motor-cylinder on the opposite side of the wing 34 via port 52, annular groove 49, pipe 46, and duct 42. Since the sleeve 32 and its wing are keyed to the 55 pin 29, which is in turn held by pin 53 passing through the pin 29 into the lug 30 on the gun, the wing 34 cannot revolve under the influence of the pressure, and the wing 44 is therefore forced to revolve around the sleeve 60 32, carrying with it the cylinder 35 and its attached rib 37, with the worm-teeth 38 and 39 thereon. The first part of this rotary movement causes the worm-teeth 38 to engage with the worm 26 upon the breech-block 65 and partially rotate it, so as to disengage the screw-thread on the block from the cor-

sponding screw-threads in the breech of the gun, after which the rack-teeth 39 on the motor engage the rack 27 on the block and withdraw said block into the tray in a manner well understood by those familiar with the art. In addition to the flange or rib 37 the motor-cylinder has thereon a vertical rib 54, extending preferably from the top to the bottom thereon and located immediately at 70 the end of the rack 39 opposite to the worm-teeth 38. At the instant when the breech-block has been fully withdrawn into the carrier-tray the face or shoulder 55 of the rib 54, adjoining the rack 39, abuts against a corresponding shoulder 56 on the carrier-tray, and the continued rotation of the motor-cylinder causes the tray to swing outward from the breech of the gun into the position shown in dotted lines in Fig. 6 and in full lines in Fig. 85 7. A pin 57 passes through the upper arm 31 of the carrier-tray and has a spring 58, normally holding it in its lowermost or depressed position. The lower point of this pin passes through a slot 59 in the motor-casing 90 40 and enters a corresponding groove 60 in the top of the motor-cylinder, which groove has a seat or depression 61 formed in one end thereof. An arm 62 projects from the upper lug 30 and has a rearwardly-opening 95 notch or slot formed therein immediately above the slot 59 in the motor-casing. The upper surface of the arm 62 is beveled, so that the lower edge of the surface adjoins the opening of the notch formed in said arm. The 100 pin 57 has a head 63 formed thereon, and this pin is held by its spring 58 with the head 63 projecting a slight distance above the surface of the carrier-tray arm 31. When the pin is in the position shown in Fig. 9, it is 105 held by the arm 62 with the nose of the pin entering the slot 60 upon the upper surface of the motor-cylinder, but elevated sufficiently so that the pin does not engage or enter into the hole 61, formed at the end of the 110 slot 60, and the motor-cylinder is therefore free to revolve independently of the carrier-tray. When, however, the shoulder 55 on the motor-cylinder strikes the shoulder 56 upon the carrier-tray and swings the latter away from the gun, the head 63 of the pin is carried off of the arm 62 and the point of the pin enters the hole or depression 61, formed in the slot 60 upon the motor-cylinder, thereby locking the motor-cylinder and 115 the tray together. Upon the reverse movement of the motor the motor and carrier-tray are thus compelled to swing together until the head 63 of the pin is forced up the incline on the arm 62 and the point of the pin 120 withdrawn from the hole 61 in the motor, which action occurs at the instant when the carrier is returned in position to present the breech-block to the breech of the gun. Upon the further movement of the motor the rack 125 39 of the motor engages the rack 37 on the breech-block, causing it to reenter the breech,

after which the teeth 28 upon the motor engage the worm 26 upon the block and turn it into its locked position.

Any suitable reservoir may be employed for storing the air compressed by the combined energy of the recoil and the gases of discharge, and any suitable means through which said energies act to compress the air in such reservoir may be employed. I prefer, however, to form the reservoir as an integral part of the pneumatic-brake cylinder and to compress the air in said reservoir by the counter-recoil action of the piston 14. The specific construction of this reservoir and air-compressing means will be best understood by reference to Fig. 13. The reservoir is here indicated at 65 as a rearward extension of the brake-cylinder 6 and separated therefrom by a partition 66, having a valve 67 opening from said cylinder 6 toward reservoir 65, while another valve 68 opens from the atmosphere into cylinder 6 at a point between partition 66 and piston 14 when said piston is in its rearmost position. Upon the discharge 25 of the gun the piston 14 moves forward and air enters cylinder 6 through valve 68 to the rear of the piston, the valve 67 being held closed by the pressure within the reservoir 65. The rearward movement of the piston 30 14 compresses the air between the piston and partition 66, whereupon the valve 68 closes and valve 67 opens, thereby permitting the air to be compressed within reservoir 65.

As before stated, the admission of motive fluid from the reservoir to the motor is controlled by the valve 48 in the valve-easing 47. (See Fig. 10.) This valve may be operated automatically by the recoil or counter-recoil movements of the gun or by hand, as may be deemed most advisable. Preferably I construct it to be shifted by the counter-recoil into position to open the breech, Fig. 10, and operated by hand to shift it into position to close the breech. For the purpose of automatically shifting the valve by the counter-recoil movement of the gun the valve is provided with a valve-stem 69, Figs. 1 and 10, having a projecting cam-surface 70 formed thereon, and the valve is so mounted upon the reservoir 65 as to locate this cam-surface 70 in the path of a corresponding cam part 71, carried by the gun, as shown in Figs. 1, 1^a, 1^b, and 1^c. In addition to the projecting cam 70 the valve-stem 69 is provided with a handle 72, by which it may be revolved or have longitudinal movements imparted to it. By turning the valve-stem the control which the valve exercises over the motor is in no way affected, but the cam-surface 70 on the stem 69 can be placed in position where the cam 71 on the gun may engage it on counter-recoil, Fig. 1^b, or said cam-surface 70 may be entirely removed from the path of cam 71. (See dotted lines, Fig. 1^b, and full lines, Fig. 1^c.) Preferably the stem is supplied with a spring 73, which normally holds it in position for the valve to be actuated by the counter-recoil.

Assuming that the breech-block is to be automatically opened upon the counter-recoil of the gun and closed by hand manipulation of the valve, the operation is as follows: The gunner grasps the handle 72 and turns the valve-stem against the tension of spring 73 until the cam-lug 70 is in the position shown in Fig. 1^c and then depresses said stem till 75 the lug 70 is behind the cam-arm 71, thereby shifting the valve 48 from the position shown in Fig. 10 to the opposite end of its casing and permitting the air to enter the motor to close the breech-block. The parts remain in 80 this position till the gun is fired, and on the recoil the cam-arm 71 is withdrawn to the rear and the spring 73 acts to turn the valve-stem 69, so as to shift the lug 70 from the dotted to the full line position, Fig. 1^b, and on the 85 counter-recoil the cam 71 contacts with cam 70 and lifts the pin, as shown in Figs. 1, 1^a, thereby shifting the valve 48 to the position shown in Fig. 10 and admitting air to the motor to open the breech, it being understood 90 that in Fig. 1 the parts are in the position they occupy the instant the valve has been moved and before the breech-block has been opened.

In Figs. 14 and 15 I have illustrated a modification in which the elastic-fluid cushion is interposed between two rotating, rather than reciprocating, parts attached one to the gun and one to the gas-chamber. In said figures the gun 1 has side ribs 74, with racks on the under sides thereof meshing with gear-teeth on the oppositely-projecting ends of a cylinder 75, supported transversely beneath the gun on a shaft 76, resting in bearings 77 on the gun-mount. The shaft 76 has a radial 105 wing 78 secured thereto and projecting into the cylinder, and the cylinder 75 has a like wing 79 secured to its inner wall and projecting toward the shaft. Preferably the wings work with air-tight contact against the cylinder and shaft, respectively. Keyed to the shaft 76 at the opposite ends of the cylinder 75 are gear-wheels 80, and rods 81 are attached to either side of the nozzle 12 and extend rearward, one on each side of the gun, and have 115 on their rear ends racks 82, engaging the gear-wheels 80, keyed to the shaft 76. In Fig. 14 is also shown side vent 83, of which there may be one in either side to vent the gas-chamber when it has moved forward the desired distance. In operation when the gun is fired the gas-nozzle acts to turn the shaft 76 and its wing 78 in one direction, and the gun acts to turn the cylinder 75 and its wing 79 in the opposite direction, compressing the air between 125 them, which on its expansion returns the parts to their normal positions. It will be understood that the space indicated at 84 may be provided with valves similar to valves 67 68, whereby air may be taken in on the recoil and 130 forced or compressed into a reservoir on the counter-recoil.

It will be seen that I have devised a very simple means for utilizing the energies of the

recoil and of the gases of discharge to operate the breech mechanism and that in operation said means also serve to materially reduce the disturbing influences of the recoil by opposing thereto the energy of the gases of discharge.

What I claim is—

1. The combination with a gun, of a recoil-actuated part, a gas-actuated part, and means 10 confining an elastic-fluid medium between said parts.

2. The combination with a gun, of a recoil-actuated part, a gas-actuated part, and means compressing an elastic-fluid medium by the 15 movements of such parts upon the discharge of the gun.

3. The combination with a gun, of a recoil-actuated piston, a gas-actuated piston, and means compressing an elastic-fluid medium 20 by the movements of the pistons upon the discharge of the gun.

4. The combination with a gun, of a recoil-actuated part, a gas-actuated part, said parts moving toward each other when the gun is 25 fired, and means confining a fluid medium between said parts.

5. The combination of a gun and gas-catching chamber moving in opposite directions when the gas is discharged, and means interposing an elastic-fluid cushion between said parts.

6. The combination of a gun recoiling rearward, with a gas-catching chamber driven forward by the gases of discharge, and means interposing an elastic-fluid cushion between said parts.

7. In a gun, the combination of a recoil-actuated part, with a gas-actuated part, and air-compressing means simultaneously actuated 40 by both of said parts.

8. The combination of a gun recoiling rearward, with a gas-catching chamber driven forward by the gases of discharge, and air-compressing means actuated by said gun and gas-chamber.

9. The combination of a gun recoiling rearward, with a gas-catching chamber driven forward by the gases of discharge, pistons connected one to the gun and one to the gas-chamber and moving toward each other when the gun is discharged, and means confining air between said pistons.

10. In a gun, the combination of a recoil-actuated part and a gas-actuated part, means 55 confining and compressing air between said parts, and devices utilizing the energy of the air thus compressed to perform work in manipulating the gun.

11. The combination with a gun and its 60 mount, of a gas-chamber carried by the gun, a recoil-cylinder carried by the mount, and means operated by the gases of discharge within the chamber for increasing the pressure in the cylinder.

65 12. The combination with a gun and its mount, of a gas-chamber carried by the gun, a recoil-cylinder carried by the mount, means

operated by the gases of discharge within the chamber for increasing the pressure in the cylinder, and means for controlling the escape 75 of the gases from the gas-chamber whereby the action of the gases is prolonged.

13. The combination with a gun and its mount, of a gas-chamber carried by the gun, having an opening for the passage of the projectile, a recoil-cylinder carried by the mount, means operated by the gases of discharge for increasing the pressure in the cylinder, and automatic means for closing the opening in the gas-chamber after the projectile has passed 80 through.

14. The combination of a gun and its mount, with a gas-chamber carried by the gun and having an opening for the passage of the projectile, a recoil-cylinder carried by the mount, 85 means operated by the gases of discharge for increasing the pressure in the cylinder, and an automatically-operated valve acting to close the chamber after the passage of the projectile.

15. The combination with a gun, of a pneumatic recoil-cylinder, and means operated by the gases of discharge for increasing the pressure in the cylinder.

16. The combination with a gun, of a pneumatic recoil-cylinder, a gas-chamber carried by the gun, means operated by the gases of discharge for increasing the pressure in the cylinder, and means for controlling the escape 95 of the gases from the gas-chamber whereby the action of the gases is prolonged.

17. The combination with a gun, of a recoil-cylinder, a piston secured to the gun and movable in the recoil-cylinder, and a second piston in rear of the first piston also movable 105 within the cylinder, and gas-operated means for moving the second piston to compress the air within the cylinder.

18. The combination with a gun, of a recoil-cylinder, a piston secured to the gun movable 110 in the recoil-cylinder, and a second piston also movable within the cylinder, a gas-chamber carried by the gun, gas-operated means for moving the second piston to compress the air within the cylinder, and means for controlling the escape of the gases from the chamber whereby the action of the gases is prolonged.

19. The combination with a gun, of a pneumatic recoil-cylinder, a piston secured to the 115 gun and movable within said cylinder, and a second piston in rear of the first piston within the cylinder forwardly driven by the gases of discharge.

20. The combination with a gun, provided 120 with a gas-chamber, of a pneumatic recoil-cylinder, a piston secured to the gun and movable within said cylinder, a second piston within the cylinder forwardly driven by the gases of discharge, and means for controlling 125 the escape of the gases from the chamber, whereby the action of the gases is prolonged.

21. The combination with a gun, of a pneumatic recoil-cylinder, a piston secured to the

gun and movable within said cylinder, a second piston within the cylinder forwardly driven by the gases of discharge, and means connected with the second piston for maintaining the pressure within the cylinder.

22. The combination with a gun, provided with a gas-chamber, of a pneumatic recoil-cylinder, a piston secured to the gun and movable within said cylinder, a second piston within the cylinder forwardly driven by the gases of discharge, means connected with the second piston for maintaining the pressure within the cylinder, and means for controlling the escape of the gases from the chamber whereby the action of the gases is prolonged.

23. The combination with a gun, of a gas-chamber carried thereby, a pneumatic recoil-cylinder, a piston secured to the gun and movable within said cylinder, a second piston in rear of the first piston, within the cylinder and operatively connected with the gas-chamber.

24. The combination with a gun, of a gas-chamber carried thereby, and movable thereon, a pneumatic recoil-cylinder, a piston secured to the gun and movable within said cylinder, a second piston within the cylinder and operatively connected with the gas-chamber.

25. The combination with a gun, of a gas-chamber carried thereby, a pneumatic recoil-cylinder, a piston secured to the gun and movable within said cylinder, a second piston within the cylinder and operatively connected with the gas-chamber, and means for controlling the escape of the gases from the gas-chamber whereby the action of the gases is prolonged.

26. The combination with a gun, of a gas-chamber carried thereby, and movable thereon, having an opening for the passage of the projectile, a pneumatic recoil-cylinder, a piston secured to the gun and movable within said cylinder, a second piston within the cylinder and operatively connected with the gas-chamber, and means for automatically closing the opening in the chamber after the projectile has passed through, to prolong the action of the gas-chamber.

27. In a breech-loading gun, the combination of the breech-block, a motor for operating the same, and means transmitting the energies of the gases of discharge and of the recoil to the motor to actuate the same.

28. In a breech-loading gun, the combination of the breech-block, a motor for operating the same, air-compressing devices actuated by the combined energies of the gases of discharge and of the recoil, and means conducting the air so compressed to the motor.

29. In a gun, the combination of a breech-block and its operating-motor, with a recoil-actuated part, a gas-actuated part, air-compressing devices simultaneously actuated by both of said parts, and means transmitting the energy of the compressed air to said motor.

30. The combination in a gun, of a breech-block, a recoil-actuated part and a gas-ac-

tuated part moving toward each other upon the discharge of the gun, means confining air between said parts whereby said air is compressed, and means utilizing the energy of said compressed air to operate the breech-block.

31. In a gun, the combination of a breech-block and its operating-motor, with a recoil-actuated piston and gas-actuated piston moving toward each other upon the discharge of the gun, means confining air between said pistons whereby said air is compressed, and means transmitting the energy of said compressed air to the motor.

32. In a breech-loading gun, the combination of a breech-block and a motor therefor, with means actuated upon the discharge of the gun for compressing a motive fluid, and valve mechanism also actuated upon the discharge of the gun and controlling the supply of motive fluid to said motor to open the breech.

33. In a breech-loading gun, the combination of a breech-block, with the motor for operating the same, a source of motive fluid, valve mechanism controlling the supply of fluid to said motor, and discharge-actuated means for operating said valve mechanism.

34. The combination of the cradle and the gun longitudinally movable therein and the gas chamber or nozzle longitudinally movable on the gun, with the brake-cylinder having one end supported by the cradle and the other end by the gun, two pistons within said cylinder and attached one to the gun and one to the gas-chamber, a compressed-air reservoir carried by said cylinder and means whereby the movements of one of said pistons serves to compress air into said reservoir.

35. The combination of the cradle, the gun supported therein, the brake-cylinder supported by the gun and cradle, the reservoir carried by the cylinder, air-compressing means actuated by the combined energies of recoil and the gases of discharge, the breech-block, the air-motor operatively connected thereto, and means controlling the passage of air from said reservoir to the motor.

36. The combination of the gun, the gas-nozzle movable longitudinally thereon and having a port in line with the bore, valves automatically closing said port as the nozzle moves forward, and means automatically opening said valves as the nozzle moves rearward.

37. The combination of the gun, the gas-nozzle longitudinally movable thereon and having a port in line with the bore, means automatically closing said port as the nozzle moves forward, and vents permitting the gradual escape of the gas from the nozzle after said port is closed.

38. The combination of the gun, the gas-nozzle longitudinally movable thereon and having a port in line with the bore, means closing said port whereby the gases of discharge move the nozzle forward, means moving said nozzle rearwardly and devices auto-

matically opening said port upon the rearward movement of the nozzle.

39. The combination of the gun, the gas-nozzle longitudinally movable thereon and having a port in line with the gun-bore, means actuated by the gases of discharge and closing said port, means opening said port, and devices timing the opening movement.

In witness whereof I have signed this specification in the presence of two subscribing witnesses.

SAMUEL N. McCLEAN.
